UNITED STATES PATENT OFFICE.

WILLIAM J. ROCHE, OF MEADVILLE, PENNSYLVANIA, ASSIGNOR TO THE SPIRELLA COMPANY, OF MEADVILLE, PENNSYLVANIA, A CORPORATION OF PENNSYLVANIA.

GARMENT-STAY.

1,213,953.

Specification of Letters Patent. Patented Jan. 30, 1917.

Application filed July 21, 1914. Serial No. 852,254.

To all whom it may concern:

Be it known that I, WILLIAM J. ROCHE, a resident of Meadville, in the county of Crawford and State of Pennsylvania, have invented a new and useful Improvement in Garment-Stays, of which the following is a specification.

This invention relates to garment stays, and particularly to wire garment stays such as are used for corsets and other like articles of wearing apparel.

The object of the invention is to provide a wire stay of the character described which can be readily manufactured, which is simple, which is very resilient and has material resistance to bending strains, and which contains a long length of wire in a stay of given dimensions, so that there is no liability of the stay taking a permanent set when subjected to short bends.

The invention comprises the stay herein-after described and claimed.

In the drawings, which represent two embodiments of the invention, Figure 1 is a plan view on an exaggerated scale of one face of the stay; and Fig. 2 is a similar view of a modified form of the invention.

The stay shown in the drawings is formed of wire, and preferably is formed of a plurality of wires 1, two being shown, which are bent back and forth alternately from edge to edge of the stay to form a series of alternately disposed loops or eyes 2 lying along the edges of the stay and a series of transversely extending crossing portions 3. The two wires are intertwined or twisted together so that the crossing portions 3 of the two wires cross each other along the middle line of the stay. Also, each crossing portion 3 of the wire, near one edge of the stay, is bent or deflected out of its normal course to form a loop or eye 4 which may be of any suitable shape or form and which is shown as a closed loop or eye formed by a complete turn of the wire. The loops or eyes 4 in the two wires are preferably oppositely disposed, or in other words, are arranged in pairs, so that there are two rows of such loops lying between the edges of the stay and disposed on opposite sides of its center line.

The closed loops or eyes 4 may be of any suitable size and in Fig. 1 are shown as small loops contained wholly within the edge loops or eyes 2.

Fig. 2 shows another arrangement in which the closed loops or eyes, indicated at 4^a, are larger and of substantially the same size as the edge loops 2 being formed by coiling the wire in spiral form at the edges of the stay, the wires forming the two oppositely disposed closed loops of a pair being closely adjacent, as at 6, along the median line of the stay. Each crossing portion of the wire may also substantially abut, near one edge of the stay, the next adjacent closed loop or eye 4^a in the other wire, as at 7, which greatly increases the resistance of the stay to edgewise bending stresses due to the inability of the wires to pass each other.

These closed loops increase the resistance of the stay to bending strains, particularly in the edgewise direction, so that the stay is very resilient and is not liable to take a permanent set on short bends.

What I claim is:—

1. A garment stay, comprising a plurality of wires, each of which is bent back and forth from edge to edge of the stay to form a series of edge loops and transversely extending crossing portions, the wires being also bent to form a series of closed loops lying on each side of the middle line of the stay.

2. A garment stay, comprising a plurality of wires, each of which is bent back and forth from edge to edge of the stay to form a series of edge loops and transversely extending crossing portions, the wires being also bent to form pairs of oppositely disposed closed loops lying on each side of the middle line of the stay.

3. A garment stay, comprising a plurality of wires, each of which is bent back and forth from edge to edge of the stay to form a series of edge loops and transversely extending crossing portions, the wires being also bent to form two longitudinally extending rows of closed loops lying on each side of the middle line of the stay, alternate loops in each row forming parts of different wires.

4. A garment stay, comprising a plurality

of wires bent back and forth across the stay to form a series of edge loops and crossing portions, the wires being also bent intermediate the edges of the stay to form a row of 5 closed loops or eyes, alternate loops or eyes of which are at different wires.

In testimony whereof, I have hereunto set my hand.

WILLIAM J. ROCHE.
